UNITED STATES PATENT OFFICE

2,582,082

FLATIRON HAVING A RETRACTABLE SUPPORT

Alfred G. Swenson, Ontario, Calif., assignor to
General Electric Company, a corporation of
New York

Application October 31, 1947, Serial No. 783,253

1 Claim. (Cl. 38—79)

1

This invention relates to flatirons and it has for its object the provision of a flatiron having improved means for supporting the iron body in an elevated rest position above the work surface, such as the surface of an ironing board.

In accordance with this invention a support for the iron is provided. This support is movable from a retracted position which it occupies during normal ironing operation to an extended position wherein it supports the pressing surface of the iron above the work surface. Means are provided for actuating the support to its extended iron body supporting position responsive to a manual upward tilting of the forward end of the iron through a predetermined degree of movement.

More specifically, over-center spring means is connected to the support and is operated to and through a critical position to shift the support from its non-operative retracted position to its extended body supporting position by means of an operating element or trigger, which is operated by its engagement with the pressing board or work surface as the iron is tilted upwardly toward its rest position. The support, spring means and trigger are returned to their initial or inoperative positions to restore the iron to condition for ironing by the relative movement between the support and iron body effected by moving the body forwardly from its rest position while the support is in contact with the work surface. In other words, the support is extended to its supporting position merely by tilting the iron body upwardly to its rest position, and is retracted merely by moving the iron forwardly from its rest position.

For a more complete understanding of this invention, reference should be had to the accompanying drawing in which Fig. 1 is a side elevation of a flatiron embodying the invention, the iron being in normal ironing relation with respect to the ironing board; Fig. 2 is a side elevation of the flatiron with the legs extended and supporting the flatiron in its elevated non-ironing position of rest; Fig. 3 is a plan view of the flatiron partly in section to show details of construction, the figure being drawn to a larger scale than are Figs. 1 and 2; Fig. 4 is a fragmentary longitudinal sectional view showing the condition of the supporting means with the flatiron in ironing position; and Fig. 5 is a view similar to Fig. 4, but illustrating the supporting means in condition to support the flatiron in its elevated or rest position.

Referring to the drawing, this invention has

been shown in one form as applied to a flatiron having an ironing body 1 which comprises a metal soleplate 2 which is heated by an electrical heating element 3 of the sheathed type, this element being substantially of hairpin shape and cast into the soleplate with the point at the forward end of the iron and with the legs extending nearly to the rear end thereof; the soleplate is provided with an upright U-shaped rib 4 which receives the element, as shown in Fig. 3. The ironing body 1 is further provided with a shell 5 covering the soleplate and an operating handle 6 on the shell. Soleplate 2 is provided with a bottom pressing surface 7 which during the ironing process is horizontal or parallel to and rests on the ironing board surface 8.

Suitable means are provided for supporting the iron in a rest position as shown in Fig. 2 in which position the pressing surface 7 makes a relatively small angle, such as about 20°, with the horizontal pressing position. This means comprises a pair of legs 9 positioned one on either side of the longitudinal axis of the iron and inside the periphery of the soleplate as shown best in Fig. 3. The legs may and are intended to move down through soleplate slots 9a to extended body supporting positions (Fig. 5) where they are substantially at right angles to the pressing surface 7. One part 13 of each leg 9 is formed into roughly a U-shape which straddles the rib 4, as shown. The outer arm 13a of the U is pivoted by means of screw 14 to a stud 15 which is an integral part of rib 4, while the inner arm 13b is pivoted to one arm of a U-shaped bracket 17 by means of a pivot 18, all as clearly shown in Figs. 4 and 5. The nexus of bracket 17 is fixed to the base of the iron by screws 18a. The arms 13b of the two legs 9 are interconnected by a pin 19 which is peened over as at 20. The foregoing arrangement pivots the legs for movement on a common transverse axis substantially at right angles to the longitudinal axis of the iron body.

The pin 19 also serves to link legs 9 with operating lever arms 21' of an operating trigger element 21. This element, as shown, is in the form of a transverse plate located at the rear of and spaced from the rear edge of the soleplate, and at its ends it is connected to the rear ends of the lever arms 21'. Lever arms 21' are connected somewhat to the rear of their midpoint to a generally U-shaped bracket 22. This bracket has its nexus fixed to the rear end of the soleplate by screws 22a, as shown, and has a pair of rearwardly extending arms 23 to the ends of which the arms are pivoted by means of rivets 24.

As shown, the forward or inner ends of levers 21' are provided with slots 25 elongated lengthwise of the arms and which function to receive the pin 19.

Also a coiled tension spring 26 is anchored at one end to the pin 19 at its midpoint and at its other end is fastened to an anchor pin 27 which is fixed in any suitable manner to the soleplate 2 at a point thereof forward of the transverse axis of movement of legs 9. This spring functions first to hold the various elements in their inoperative positions of Figs. 3 and 4 wherein the legs 9 are in their retracted or inoperative positions. That is, the spring holds the legs retracted with the nexus of the legs abutting the rib 4, which rib functions as a stop; and also holds the trigger 21 in the position of Fig. 4. With the parts thus arranged, the iron may be used to press in the usual way without interference from the support mechanism.

Now, if it is desired to support the iron in its elevated rest position of Fig. 2, the forward end of the iron is tilted upwardly by means of handle 6. This tips the iron body backwardly about a transverse axis at the rear edge of the soleplate, and as a result the trigger plate 21 is moved down to contact the ironing surface 8; thereafter, as the iron body is tilted the trigger is forced counterclockwise with reference to the iron body since it no longer can move relative to the ironing board 3, and this movement of the trigger pivots the arms 21' counterclockwise about rivets 24. This movement of the levers 21' causes their forward ends to be lowered and, as a result, they carry the pin 19 downwardly, this movement of the pin being permitted since it may slide in the elongated slots 25 as it arcs downwardly. This downward movement of the pin 19 rotates the legs 9 clockwise with respect to the iron body, that is, it moves the legs downwardly and forwardly to their extended body supporting position of Fig. 5, and wherein the iron body is supported on the legs 9 and the heel edge of the body. It will be observed that when the legs are in this position they are generally vertical; more specifically, they are substantially at right angles to the plane of the pressing surface 1. The spring 26 at first tends to retard the motion of the levers 21' and the downward motions of the pin 19 and legs 9; and retards these movements until the anchor point of the spring on pin 27, pivot axis of rivet 18 and pin 19 are in alignment, which is the neutral or critical position of the elements and beyond which the spring assists in extending the legs 9 to their fully extended position of Fig. 5. The legs are stopped in this position by the engagement of pin 19 with recesses 27a formed in the bracket 17.

When it is desired to return the flatiron from the rest position of Fig. 5 to the ironing position of Fig. 4, the iron handle is grasped and the iron pushed forwardly and the nose lowered; the body pivoting, so to speak, on the legs 9. This action causes the legs 9 to pivot to the rear since their lower ends are in engagement with the pressing surface 8 and cannot move forwardly with the iron body. This counterclockwise motion of the legs with reference to the iron body is against the action of the spring 26 which retards their motion until the spring again reaches the critical position. When the spring has been moved

slightly beyond this position the spring snaps the legs to their fully retracted position of Fig. 4.

While I have shown a particular embodiment of my invention, it will be understood, of course, that I do not wish to be limited thereto since other modifications may be made, and I, therefore, contemplate to cover by the following claim such modifications as may be made by one skilled in the art and which fall within the spirit and scope of my invention.

What I claim as new and desire to secure by Letters Patent of the United States is:

A flatiron comprising an ironing body including a soleplate having a pressing surface operable in a normal substantially horizontal position on an ironing work surface, the soleplate at its rear end being provided with two longitudinally extending slots which extend along the side edges of the soleplate, studs on the soleplate, one adjacent to the inner end of each slot, each stud having a flat surface at a slot edge and at right angles to the plane of the pressing surface, supporting legs pivoted on said flat surfaces adapted to move through said slots between a flatiron supporting position outside the flatiron and a non-supporting position within the confines of the ironing body, the inner ends of said supporting legs beyond their pivots being shaped to provide U-shaped ends, a bracket carried by the soleplate having spaced upstanding ears on which the inner arms of said U-shaped ends are pivoted, a pivot pin connecting said arms at points to the rear of their pivot connections to said ears and so located that the pivot pin moves from a position above said pivot connections to a position below such pivot connections when said supporting legs are moved from non-supporting position to supporting position, a bracket fixed at the rear end of the soleplate, an operating trigger pivoted on said bracket and provided at its inner end with a lengthwise elongated slot through which said pin extends to provide a lost motion connection between the operating trigger and the pin, the outer end of said operating trigger projecting outwardly and downwardly with respect to the plane of the soleplate to a position such that its end may engage an ironing surface when the flatiron is tilted rearwardly, and an overcenter spring fastened at one end to the soleplate and at the other end to said pin which when the supporting legs are moved between non-supporting and supporting positions moves from one side of dead center to the other whereby it serves to hold the supporting legs in either of their two positions, said elongated slots serving to permit lengthwise movement of said pin and trigger with respect to each other when the supporting legs are moved between non-supporting and supporting positions.

ALFRED G. SWENSON.
